TYPEWRITER

Karl T. Baughman, Lake Forest, Ill., assignor to Sears, Roebuck & Co., Chicago, Ill.

Filed Jan. 4, 1973, Ser. No. 321,051

Term of patent 14 years

Int. Cl. D18—01

U.S. Cl. D64—11 A

Fig. 1

FIG. 1 is a front perspective view of a typewriter showing my new design;

FIG. 2 is a rear perspective view thereof;

FIG. 3 is a left side elevational view thereof;

FIG. 4 is a right side perspective view thereof; and

FIG. 5 is a rear elevational view thereof.

Conventional operating mechanism and support means for the carriage have been omitted for convenience of illustration.

I claim:

The ornamental design for a typewriter, as shown and described.
